Term of patent 14 years

(Cl. D26—5)

FIG. 1

FIG. 2

FIG. 3

FIG. 4

FIG. 5

FIG. 1 is a perspective view of a computer console, showing my new design;

FIG. 2 is a front elevational view;

FIG. 3 is a side elevational view, the opposite side being substantially a mirror image thereof;

FIG. 4 is a cross-sectional view of the support member taken along the line 4-4 in FIG. 3; and

FIG. 5 is a top plan view thereof.

A portion of the upright support is broken away for convenience in illustration to disclose the preferred extent of the supporting structure which in the illustrated embodiment extends from the floor to the ceiling.

I claim:

The ornamental design for a computer console, substantially as shown and described.
